CLAIM

The ornamental design for a plateau vase with constant size neck, as shown and described.

DESCRIPTION

FIG. 1 is a perspective view of a first embodiment of a plateau vase incorporating my new design;

FIG. 2 is a front elevation view thereof, with the right side, left side, and back elevation views being identical thereto;

FIG. 3 is a top plan view thereof;

FIG. 4 is a bottom plan view thereof;

FIG. 5 is a cross-sectional view thereof, taken along line 5-5 of FIG. 2, viewed in the direction of the arrows;

FIG. 6 is a cross-sectional view thereof, taken along line 6-6 of FIG. 2, viewed in the direction of the arrows;

FIG. 7 is a cross-sectional view thereof, taken along line 7-7 of FIG. 2, viewed in the direction of the arrows;

FIG. 8 is a perspective view of a second embodiment of a plateau vase incorporating my new design;

FIG. 9 is a front elevation view thereof, with the right side, left side, and back elevation views being identical thereto;

FIG. 10 is a top plan view thereof;

FIG. 11 is a bottom plan view thereof;

FIG. 12 is a cross-sectional view thereof, taken along line 12-12 of FIG. 9, viewed in the direction of the arrows;

FIG. 13 is a cross-sectional view thereof, taken along line 13-13 of FIG. 9, viewed in the direction of the arrows;

FIG. 14 is a cross-sectional view thereof, taken along line 14-14 of FIG. 9, viewed in the direction of the arrows;

FIG. 15 is a perspective view of a third embodiment of a plateau vase incorporating my new design;

FIG. 16 is a front elevation view thereof, with the right side, left side, and back elevation views being identical thereto;

FIG. 17 is a top plan view thereof;

FIG. 18 is a bottom plan view thereof;

FIG. 19 is a cross-sectional view thereof, taken along line 19-19 of FIG. 16, viewed in the direction of the arrows;

FIG. 20 is a cross-sectional view thereof, taken along line 20-20 of FIG. 16, viewed in the direction of the arrows; and,

FIG. 21 is a cross-sectional view thereof, taken along line 21-21 of FIG. 16, viewed in the direction of the arrows.
